(57) **CLAIM**

The ornamental design for a loudspeaker, as shown and described.

DESCRIPTION

FIG. 1 is a front perspective view of a loudspeaker, showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is a rear perspective view thereof;

FIG. 9 is an enlarged view of the encircled portion 9 in FIG. 1; and,

FIG. 10 is an enlarged view of the encircled portion 10 in FIG. 2.

The broken lines in the figures depict portions of the loudspeaker that form no part of the claimed design. The dot-dash broken lines in the figures represent a boundary of the claimed design and form no part of the claimed design. The dot-dot-dash broken lines encircling enlarged portions of the claimed design form no part of the claimed design.
